Primary Examiner — Katrina A Betton(74) *Attorney, Agent, or Firm* — Brinks Gilson & Lione(57) **CLAIM**

We claim the ornamental design for a cover used for windshield wiper connectors, as shown and described.

DESCRIPTION

FIG. 1 is a top left side perspective view of a cover used for windshield wiper connectors showing our new design;

FIG. 2 is a right elevation view thereof;

FIG. 3 is a left elevation view thereof;

FIG. 4 is a front elevation view thereof;

FIG. 5 is a back elevation view thereof;

FIG. 6 is a top plan view thereof; and,

FIG. 7 is a bottom plan view thereof.

The ornamental design which is claimed is shown in solid lines in the drawings. The broken lines showing of portions of the article forms no part of the claimed design.

1 Claim, 7 Drawing Sheets(56)
